UNITED STATES PATENT OFFICE.

HENRY LOFTIE, OF SYRACUSE, NEW YORK.

WINDOW AND PICTURE HOOK.

SPECIFICATION forming part of Letters Patent No. 378,891, dated March 6, 1888.

Application filed July 9, 1887. Serial No. 243,819. (No model.)

To all whom it may concern:

Be it known that I, HENRY LOFTIE, of Syracuse, county of Onondaga, in the State of New York, a citizen of the United States, have invented certain new and useful Improvements in Window and Picture Hooks, of which the following is a specification, reference being had to the accompanying drawings, in which—

Figure 1 is a front elevation thereof. Fig. 10 2 is a vertical longitudinal section, and Fig. 3 is a top plan view.

My invention relates to that class of implements commonly known as combination implements.

15 My object is to produce an implement adapted to many different purposes in a dwelling or place of business; and it consists in the several novel features of construction and operation hereinafter described, and which are 20 specifically enumerated in the clauses of claim hereinafter set forth.

It is constructed as follows:

A is a tubular shank to receive the handle upon one side, flattened and corrugated or 25 roughened to adapt it for use in lighting matches, as at 1. The upper end of the bore of the shank opens outward, forming a hole, 3, which can be used to hold a taper for lighting gas, &c. Upon the right side of the shank is 30 the ring 4, and connected to the ring is the elongated hook 5, in the top of which is a small opening, 6. Upon the left side of the shank are the two jaw-pieces 7, connected to

gether, and connected to the outer jaw-piece is the stud 8, carrying the ball 9 upon its outer 35 end.

It is operated as follows: When I desire to lower or raise the upper sash of a window, I insert the knob and stud into a socket set into the top bar of the sash and either pull down 40 or push up. To light the gas, I insert a lighted taper into the hole 3, or a lighted match into the opening 6, and turn the key of the gas-fix- 45 ture with the jaws 7. To put up or take down a picture, I insert the hook 5 through the cord and support the picture on the hook until placed where desired, and to dust off the ceilings or walls, cornices, moldings, &c., of a room, I pass the handle of the duster, inverted, 50 down through the ring 4, and I can tie or otherwise fasten the handle of the duster to the handle of the implement, if desired.

What I claim as my invention, and desire to secure by Letters Patent, is—

An implement comprising a shank pro- 55 vided with a hole, 3, a handle-socket, jaws 7, a stud, 8, secured to the shank, a ring, 4, and a hook, 5, (provided with opening 6,) also se- 60 cured to the shank, substantially as described, for the purposes set forth.

In witness whereof I have hereunto set my hand this 15th day of December, 1886.

HENRY LOFTIE.
